CLAIM

The ornamental design for a combined container and cap with brush, as shown and described.

DESCRIPTION

FIG. 1 is a perspective view of a combined container and cap with brush showing our new design;

FIG. 2 is a front elevation view thereof;

FIG. 3 side elevation view thereof;

FIG. 4 is a rear elevation view thereof;

FIG. 5 is a top plan view thereof;

FIG. 6 is a bottom plan view thereof;

FIG. 7 is an exploded perspective view thereof;

FIG. 8 is a front elevation view of FIG. 7;

FIG. 9 is a side elevation view of FIG. 7; and,

FIG. 10 is a rear elevation view of FIG. 7.

The bristles are omitted in FIG. 6 for clarity of illustration.
